David Hawes
INVENTOR

BY Victor J. Evans
ATTORNEY

WITNESS: Joseph A. Nolan

UNITED STATES PATENT OFFICE.

DAVID HAWES, OF PHILADELPHIA, PENNSYLVANIA.

GARTER.

Application filed July 7, 1922. Serial No. 573,289.

To all whom it may concern:

Be it known that I, DAVID HAWES, a citizen of the United States, residing at Philadelphia, in the county of Philadelphia and State of Pennsylvania, have invented new and useful Improvements in Garters, of which the following is a specification.

This invention relates to hose supporters or garters and has for its principal object 10 to produce a device of this character which will clamp the material or hose without the necessity of puncturing, tearing or otherwise injuring the same.

Another object of the invention is to produce 15 a hose supporter having a clamp member bent to provide jaws for engaging the hose or material and an adjustable oval ring passing over said jaws for holding them in locking engagement upon the material.

20 A still further object of the invention is to produce a hose supporter or garter having a protective strip sewed or otherwise secured to one of the free ends of the elastic band and said strip is slit adjacent its lower 25 end to provide a strap which receives one of the jaw members, so that the hose or material may be securely held between the clamping jaws.

This invention also consists in certain 30 other features of construction and in the combination and arrangement of the several parts, to be hereinafter fully described illustrated in the accompanying drawings and specifically pointed out in the appended 35 claims.

In describing my invention in detail reference will be had to the accompanying drawings wherein like characters of reference denote like or corresponding parts in 40 the several views, and in which:—

In the drawings:

Figure 1 is a front elevation of the invention as applied to a hose.

Figure 2 is a perspective view of the invention.

Figure 3 is an enlarged detail view of the clamping means.

Figure 4 is a sectional view taken on line 4—4 of Figure 1.

50 Referring now to the drawing wherein like characters of reference denote corresponding parts 10 indicates an elastic band having its free ends passing through an

elliptical eye 10' and one of said ends being folded laterally upon itself and passed 55 through an adjustable buckle 11 while the opposite end depends inwardly and downwardly and passes through a bail 12 and is folded upon itself and sewed together as at 13. A protective strip 14 is sewed to the 60 depending end of the elastic band as at 15 and has its lower end slit as at 16 to provide a guiding strap 17.

A clamp 18 is bent intermediate its ends and passes over said bail to provide clamping 65 jaws 19, one of the jaws is passed through the guiding strap and has its lower end slightly curved as at 20 while the remaining jaw has its lower end curved to provide a bight 21. An oval ring shaped 70 member 22 surrounds the clamping jaws, so that when the material is placed between the jaws the ring shaped member will be passed downwardly toward the guiding strap and thereby hold the jaws in clamping position 75 upon the material.

From the above it will be seen that when a band is placed around the limb of the user and the material placed between the jaws and the user of the device slides the oval 80 ring downwardly over the jaws the material will be effectively clamped therebetween and held in this position until the operator or user of the device raises the oval ring upwardly along the clamping member.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A garter clasp comprising in combination a protecting strip, a pair of clamping jaws, a guiding strap formed on said protecting strip for engaging over one of said jaws adjacent to its free end, said jaws being resilient and tensioned to normally spread them, the jaw other than the one engaged beneath said strap having its free end bent transversely and extended beyond the free end of the strap engaged jaw, and a confining ring slidable along said jaws.

2. A garter clasp comprising in combination with a strip of elastic, of a protecting strap stitched to said strip of elastic, a substantially oval-shaped link carried by said strip of elastic, a pair of clamping jaws carried by said link, a slide ring movable along said clamping jaws, said protective
- strip having a guiding strap cut therefrom adjacent to its free end, one of said clamping jaws engaged beneath said guiding strap.

In testimony whereof I affix my signature.

DAVID HAWES.
